O. STENERSEN.

TOOL.

APPLICATION FILED JAN. 9, 1914.

1,133,587.

Patented Mar. 30, 1915.

UNITED STATES PATENT OFFICE.

OLE STENERSEN, OF BROOKLYN, NEW YORK, ASSIGNOR OF ONE-HALF TO OLAF P. OLSEN, OF BROOKLYN, NEW YORK.

TOOL.

1,133,587.

Specification of Letters Patent. Patented Mar. 30, 1915.

Application filed January 9, 1914. Serial No. 811,155.

To all whom it may concern:

Be it known that I, OLE STENERSEN, a citizen of the United States, and residing at Brooklyn, in the county of Kings and State of New York, have invented certain new and useful Improvements in Tools, of which the following is a specification such as will enable those skilled in the art to which it appertains to make and use the same.

10 This invention relates to mechanics' and draftsmen's tools or instruments, and the object thereof is to provide an improved device of this class which may be used as an ordinary compass, dividers, or as proportional dividers, also for measuring the inner diameter of tubes and the outer diameter of tubes, cylindrical bars, rods and the like, and with this and other objects in view, the invention consists in a tool or implement 20 of the class specified constructed as hereinafter described and claimed.

The invention is fully disclosed in the following specification of which the accompanying drawing forms a part, in which the 25 separate parts of my improvement are designated by suitable reference characters in each of the views, and in which;—

Figure 1 is a side view of my improved tool or instrument in its simplest form; 30 Fig. 2 a view similar to Fig. 1, but showing the parts in a reversed position; Fig. 3 a partial section on the line 3—3 of Fig. 2; Fig. 4 a section on the line 4—4 of Fig. 2; Fig. 5 a view similar to Fig. 1, but showing 35 a modification designed for use as proportional dividers; Fig. 6 a section on the line 6—6 of Fig. 5, and Fig. 7 a section on the line 7—7 of Fig. 6.

In the practice of my invention, as shown 40 in Figs. 1 to 4 inclusive, I provide a tool *a* of the class specified comprising two similar members *a*² of the same length and consisting of straight central portions provided at one end with curved arm portions *a*³ and 45 the opposite ends of which are pointed, as shown at *a*⁴. Each of the members *a*² is provided with a central longitudinal slot *a*⁵ through which is passed a screw *b* provided at one end with a head *b*² adjacent to which 50 is a cylindrical portion *b*³, which fits in the slots *a*⁵ and on which the members *a*² are free to turn, and said screw is also provided with a milled nut *b*⁴ and washer *b*⁵.

Mounted in the slot *a*⁵ of one of the members *a*² is a sliding and detachable pencil

holder *c* adapted to receive a pencil *d*, and the pencil holder *c* is formed of sheet metal and is open at one side and provided with laterally directed flanges *c*² at its opposite ends, adapted to be passed through the slot *a*⁵ by compressing the open sides thereof, and when the pressure is removed, the open side edge portions of said pencil holder will expand and the flanges *c*² will fit in corresponding recesses *c*³ in the inner side of 60 the member *a*² with which the pencil holder is connected.

The use of this device as a compass or divider will be the same as the use of others of its class, and the pencil *d* may be adjusted 70 into any desired position in the holder *c*.

In using this device for the purpose of measuring the inner diameter of a tube, the curved arms *a*³ are inserted into said tube and the pointed ends of the parts *a*² are separated so that the ends *a*⁶ of said arms will bear on the inner walls of the tube, and the distance between the pointers or ends *a*⁶ of the arms *a*² will give the inner diameter of the tube, and the screw *b* being adjustable 80 in the slots *a*⁵, the separate members *a*² may be so adjusted that the pointed ends *a*⁴ of the parts *a*² will also give the exact inner diameter of the tube.

In order to measure the diameter of a 85 rod, bar or similar device, the position of the parts *a*² is reversed, as shown in Fig. 2, and the end of the bar, rod or similar device is inserted between the arms *a*³, as indicated in dotted lines at *d*², after which the said 90 bar, rod or similar device is moved outwardly between the ends *a*⁶ of the arms *a*³, and the distance between said ends of the arms *a*³ will give the exact diameter of said 95 rod, bar or similar device, and the screw *b* may be so adjusted in the parts *a*² that the pointed ends *a*⁴ of said parts will also, and at the same time, give the exact diameter of 100 said rod or bar.

This device may also be used as an ordinary square, as a bevel or miter gage, and suitable scales or scale marks may be provided in connection with the parts *a*², and the head *b*² of the screw *b* or the washer *b*⁵, as in other devices of this class, to adapt the 105 said tool for any of the purposes specified, and said washer *b*⁵ may be made non-rotatable if desired.

In Figs. 5 to 7 inclusive, I have shown my improved tool adapted for use as propor- 110

tional dividers as well as for other uses for which tools or instruments of this class are designed, and in this form of construction, the parts or members a^2 are made longer, 5 and one side wall of the slot a^5 in one of said parts is provided with a rack gear e , and mounted in said slot a^5 in said part is a block f which is slideable in said slot and through which is passed a pin g provided 10 with a pinion g^2 which meshes with the rack gear e , and said pin is also provided at its outer end with a milled head g^3 .

A sliding block h is also mounted in the slot a^5 in the other part or member a^2 , and a 15 pin i is passed through the blocks f and h and through the slots a^5 in the parts or members a^2 and provided with a milled nut i^2 between which and the block h is placed a friction, sleeve washer i^3 . The blocks f and h are also 20 provided with outside flanges f^2 and h^2 which bear on the parts a^2 , and said blocks f and h and their connected parts constitute, as a whole, a sliding and adjustable element by which the parts or members a^2 25 of the tool are connected, and by means of which both of said parts or members may be adjusted into any desired position relative to said element, or said element adjusted into any desired position relative to said 30 parts or members.

One side of one of the parts a^2 of this tool is provided with a scale j , and is marked "inside dia.", meaning inside diameter, and the other part of said member is provided 35 with a scale k , and is marked "outside dia.", meaning outside diameter, and the block h is provided on the end thereof adjacent to the pointed ends of the part a^2 of the tool with a projection m having a mark m^2 40 adapted to be used in connection with the scales j and k . It must be understood, that the parts a^2 of the tool are of the same length, and the use of this device in measuring the inside diameter of a tube, or the 45 diameter of a rod, bar or similar device, will be the same as with the construction

shown in Figs. 1 to 4 inclusive, it being understood that all adjustments are effected by the central element or member involving the blocks f and h and their connected parts. One of the parts or members a^2 is also provided adjacent to the pointed end thereof with a pin n movable in the transverse slot o in the corresponding face of the other part or member a^2 , and the object of this construction is to provide means for holding the parts or members a^2 in proper position in the adjustment of the central member, or the operation thereof. It must be also understood that this method of using the parts or elements a^2 of the tool, or the construction by which it is effected, is not of my invention, the same being well known in other tools of this class.

I also provide one of the curved arms a^3 65 with a cutting edge a^7 by means of which the device is adapted to serve as a pencil sharpener and for other purposes.

Having fully described my invention what I claim as new and desire to secure by 70 Letters Patent is:—

A tool of the class described comprising two parts or members pivotally, slidably and adjustably connected, said parts being provided with central, longitudinal slots, 75 and a pencil holder adapted to be connected with one of said parts and designed to hold a pencil parallel therewith, said holder being approximately tubular in form and being open at one side and provided with flexible members adapted to be passed through the slot in said part and to be folded around the side portions thereof and which fit in recesses in the backs of said side portions.

In testimony that I claim the foregoing 85 as my invention I have signed my name in presence of the subscribing witnesses this 2nd day of January 1914.

OLE STENERSEN.

Witnesses:

C. MULREANY,
S. ANDREWS.
